UNITED STATES PATENT OFFICE.

LESLIE JOHN HANCOCK AND THOMAS REGINALD HANCOCK, OF WALLINGTON, ENGLAND, ASSIGNORS TO OSCAR VIVIAN ASHER, OF LONDON, ENGLAND.

ELECTRIC FURNACE.

Application filed September 11, 1922. Serial No. 587,442.

To all whom it may concern:

Be it known that we, LESLIE JOHN HANCOCK and THOMAS REGINALD HANCOCK, of Melbourne Works, Wallington, in the county of Surrey, England, British subjects, have invented certain new and useful Improvements in Electric Furnaces, of which the following is a specification.

This invention has for its object to cheapen and simplify the construction of electric furnaces by obviating the use of the wire electrical resistance coils generally employed in such apparatus.

According to this invention a series of longitudinally disposed rods of carbon or graphite surrounds a tube of refractory material, the interior of which constitutes the heating space, said rods being suitably connected together in any required order at their ends and being preferably insulated from one another and from said tube by refractory material of high melting point such as alundum. Preferably the tubular core and its surrounding rods and insulation are enclosed within a chamber packed with magnesia, kieselguhr or like non-conductor.

In one form of the invention the carbon or graphite rods are disposed in a circular series of longitudinally extending apertures formed in the wall of a tube of alundum, said apertured tube being shorter in length than the tube which constitutes the heating chamber but being adapted to fit thereover. If desired the carbon rods may be protected from oxidation by treating them in any well known manner.

The invention will be described with reference to the accompanying drawings of which Figure 1 is a longitudinal sectional elevation on the line 1-1 of Figure 2 and Figure 2 is a cross sectional elevation on the line 2-2 of Figure 1. As shown on the drawings a tube *a* of carbon or like refractory insulating material forms the muffle of the furnace and is surrounded by a coaxial tube *b* of similar material but of greater diameter and smaller length. Within the annular space between the tubes *a* and *b* is arranged a circular series of longitudinally disposed carbon or graphite rods *c¹*, *c²* . . . the ends of which are mounted respectively in two sets of arcuate carbon or graphite

blocks *d¹*, *d²* . . . and *e¹*, *e²* . . . 55 (the positions of the blocks *e¹*, *e²* . . . being shown in broken lines in Figure 2) secured by means of heat resisting and electrically insulating cement (not shown) in said annular space and near the respective ends thereof.

The rods *c* and arcuate blocks *d* and *e* are so arranged that an electric current entering the block *d¹* may flow through the rods and blocks in succession in zig-zag 65 fashion around the series to the return lead connected with the block *d⁵*.

The tubes *a* and *b* are retained in position by means of two end plates *f*, *g* which are held together by longitudinal tie bars 70 *h* . . . and nuts *j*. The end plates *f* and *g* are centrally apertured so as to fit over the ends of the muffle tube *a* whilst the outer tube *b* is clamped between said end plates *f* and *g*. The end plate *f* may 75 be apertured and bushed in any usual manner for the passage therethrough of leads such as *k* adapted to connect the blocks *d¹* and *d⁵* with a source of electric energy.

Surrounding the outer tube *b* is a casing 80 *m* which may be clamped between the end plates *f* and *g* as shown and the annular space between the tube *b* and the casing *m* may be lightly packed with magnesia, kieselguhr or like non-conductor of heat (not 85 shown) to serve as a lagging.

If desired the muffle tube *a* may be further secured to the end plates *f* and *g* by means of nuts or the like (not shown) in threaded engagement with the ends of said tube *a*.

By suitably arranging the size of the rods *c* and their connections with the arcuate blocks *d* and *e*, an electric furnace as hereinbefore set forth may be adapted 95 for operation with an electric current of any desired voltage.

Having thus described the invention, what is claimed as new is:-

1. An electric resistance furnace comprising in combination a muffle chamber, a surrounding chamber shorter in length than said muffle chamber and a series of conducting rods located between said chambers. 100

2. An electric resistance furnace comprising in combination a muffle chamber, a surrounding chamber shorter in length than said muffle chamber, insulating material be- 105

tween said chambers and conducting rods located within said insulating material.

3. An electric resistance furnace comprising in combination a chamber of refractory material, a series of conducting rods in proximity to said chamber, and arcuate blocks electrically connecting said rods together.

4. An electric resistance furnace comprising in combination a muffle chamber, a surrounding chamber shorter in length than said muffle chamber, end plates surrounding said muffle chamber in proximity to its ends and bearing on the ends of said surrounding chamber and a series of conducting rods located between said chambers.

5. An electric resistance furnace comprising in combination a muffle chamber, a surrounding chamber shorter in length than said muffle chamber, end plates surrounding said muffle chamber in proximity to its ends and bearing on the ends of said surrounding chamber, a series of conducting rods located between said chambers and a casing around said surrounding chamber, said casing being packed with heat insulating material.

6. An electric resistance furnace comprising in combination a muffle chamber, a surrounding chamber shorter in length than said muffle chamber and a series of conducting rods located between said chambers and electrically connected together to form an elongated resistance element.

35 7. An electric resistance furnace comprising in combination a muffle chamber, a surrounding chamber shorter in length than said muffle chamber and a series of conduct-

ing rods located between said chambers and electrically connected together at their ends whereby an electric current may enter at the end of one rod, traverse this rod, pass to the adjacent rod and traverse it from end to end, and likewise each successive rod.

8. An electric resistance furnace comprising in combination, a muffle chamber, a surrounding chamber shorter in length than said muffle chamber, insulating material between said chambers and in contact with both of them, and conducting rods located within said insulating material.

9. An electric resistance furnace comprising in combination a muffle chamber, a surrounding chamber shorter in length than said muffle chamber, insulating material between said chambers and in contact with both of them, and plates surrounding said muffle chamber in proximity to its ends and bearing on the ends of said surrounding chamber, and a series of conducting rods located between said chambers.

10. An electric resistance furnace comprising in combination a muffle chamber, a surrounding chamber shorter in length than said muffle chamber, a surrounding chamber shorter in length than said muffle chamber, insulating material between said chambers and in contact with both of them, and a series of conducting rods located between said chambers and electrically connected together to form an elongated resistance element.

In testimony whereof we affix our signatures.

LESLIE JOHN HANCOCK.
THOMAS REGINALD HANCOCK.
